IRA H. SPENCER, OF WEST HARTFORD, CONNECTICUT, ASSIGNOR TO THE SPENCER TURBINE CLEANER COMPANY, OF HARTFORD, CONNECTICUT, A CORPORATION OF CONNECTICUT.

CLEANING APPARATUS.

1,161,263.

Specification of Letters Patent.

Patented Nov. 23, 1915.

Application filed January 17, 1912. Serial No. 671,634.

To all whom it may concern:

Be it known that I, IRA H. SPENCER, a citizen of the United States, and a resident of West Hartford, in the county of Hartford and State of Connecticut, have invented a new and Improved Cleaning Apparatus, of which the following is a specification.

My invention relates to the class of devices used for cleaning by the employment 10 of a current of air, usually suction, and an object of the invention, among others, is to provide a device in which the dust and dirt collected from an apartment together with the air may be completely carried from the 15 apartment.

One form of device embodying the invention and in the construction and use of which the object above set out, as well as others, may be attained, is illustrated in the accompanying drawings, in which the figure is a 20 view in elevation of an apparatus embodying my invention with parts cut away to show construction.

In the accompanying drawings the numeral 3 denotes a casing containing any suitable mechanism for creating a current of air which is caused to flow inward through the inlet pipe 4 and outward through the exhaust pipe 5, the mechanism being driven as 25 by a motor 6 supported on the casing.

A separator base including a neck 7 is secured to a projecting part from the casing 3, this base having a conducting pipe 8 extending upwardly therefrom and opening at its 35 upper end within a jacket, the passage through this conducting pipe communicating with the outlet from the base and inlet pipe 4. A projection 9 from the upper end of the jacket 10 has an inlet tangentially 40 disposed, to which projection connections as with hose and cleaning tools, the latter not being shown, may be had.

A dirt receptacle 11 is removably secured to the underside of the separator base, the 45 lower tapered end 12 of this receptacle leading into an outlet 13 having a valve 14 and extending to the usual sewer outlet 15. The valve has a handle 16 by means of which it may be operated. The numeral 17 denotes 50 the usual vent for the trap 18 of the sewer connection.

The exhaust 5 opens into a connection 19 which leads to the sewer outlet 15. A tube 20 projects downwardly within the connection 19, the upper end of this tube having

a valve 21 connected by a rod 22 with a diaphragm 23 located in a shell 24. The chamber within the shell and above the diaphragm communicates as by a pipe 25 with the interior of the casing 3.

A water supply pipe 26 is connected with the shell 24 to supply water to the tube 20, and water supply pipes 27-28 are also employed for supplying water to the dirt receptacle 11, the supply to the pipes 27 and 28 being as from a main pipe 29 having a valve 30. The pipe 27 has a valve 31.

A valve 32 closes the opening through the separator base, this valve being preferably located within the dirt receptacle 11 and being preferably of curved or cylindrical form so that the incoming litter or dirt will not lodge upon it. Any suitable means for operating the valve may be employed, as herein shown a valve rod 33 extending upwardly through the jacket and top thereof being used.

In the operation of the device the valve 14 being closed, the suction created by the mechanism in the casing 3 draws the dirt 80 and dust collected by the cleaning tools in at the inlet 9, the heavier particles of which settle through the jacket 10 into the dust receptacle 11, and the lighter particles being carried through the conducting pipe 8 and 85 shell 3 to the exhaust 5 and into the connection 19. Water is supplied through the pipe 26 and tube 20 to thoroughly saturate the air and carry the dirt downward into the sewer outlet 15, it being noted that the arrangement of the diaphragm 23 connected with the valve 21 automatically operates the valve, which is opened to an extent depending upon the degree of pressure within the shell 3. When it is desired to remove the 90 contents from the receptacle 11 the valves 31 and 30 are opened producing water enough to carry the contents of the receptacle 11 through the outlet 13 and valve 14, the latter having been opened for the purpose. The valve 31 may then be closed and the water flowing through the pipe 28 will 95 thoroughly clean the lower part of the receptacle.

If it should be found that the dirt is not 105 easily dislodged the valve 32 may be closed and a tight compartment will thus be provided within which full water pressure may be exerted to force the dirt through the outlet 13. This valve also enables the recepta- 110

cle 11 to be cleaned without stopping the running of the apparatus, the closing of the valve preventing a suction upward from the receptacle when the valve 14 is opened for the purpose of emptying the contents. In fact, it will be noted that should the valve 14 be opened the entry of air therethrough will automatically close the valve 32 to effect the desired result.

10 The air thoroughly relieved from all particles of dust and dirt travels upward through the usual vent opening 17 for the trap.

15 An apparatus to embody my invention need not be constructed in exact accordance with that herein shown and described, as I contemplate variations from the construction as within the spirit and intent of the invention.

20 I claim,

1. In combination with a connection to a sewer, means for producing a current of air, a separator connected with said current producing means, means for introducing material to the separator, a dust receptacle, a connection for the passage of material from the separator to said receptacle, a connection for the passage of material from said receptacle to said sewer connection, a 25 valve located in the connection from said receptacle and a connection between said current producing means and sewer connection.

2. In combination with a connection to a sewer, means for producing a current of air, a separator connected with said current producing means, means for supplying material to the separator, a dust receptacle, a connection for the passage of material from the separator to said receptacle, a connection for the passage of material from said receptacle to the sewer connection, a valve in the connection from said receptacle, means for supplying water to 35 said receptacle to wash the material therefrom, and a connection between said current producing means and sewer connection.

3. In combination with a connection to a sewer, means for producing a current of air, a separator connected therewith, a dust receptacle, a connection for the passage of material from the separator to said receptacle, a connection for the passage of material from said receptacle to the sewer connection, a valve in the connection from said receptacle, means for supplying water to the top and bottom of said receptacle to wash the material to the sewer, and a connection between said current producing means and sewer connection.

4. In combination with a connection to a sewer, means for producing a current of air, a separator connected therewith, a dust receptacle, a connection for the passage of material from the separator to said recep-

tacle, a connection for the passage of material from said receptacle to the sewer connection, a valve in the connection from said receptacle, means for supplying water to the top and bottom of said receptacle to wash the material to the sewer, a valve to control the supply of water to the top of said receptacle, and a connection between said current producing means and sewer connection.

75 5. In combination with a sewer connection, means for producing a current of air, a separator connected with said current producing means, a dust receptacle, a connection for the passage of material from the separator to said receptacle, a connection for the delivery of material from said receptacle to the sewer connection, and a connection between the exhaust of said current producing means and said sewer connection.

6. In combination with a sewer connection, means for producing a current of air, a separator connected with the current producing means, a dust receptacle, a connection for the passage of material from the separator to said receptacle, means for delivering material collected in said receptacle to said sewer connection, a connection between the exhaust of said current producing means and the sewer connection, and means 95 for introducing water to said exhaust.

7. In combination with a connection to a sewer, means for producing a current of air, a separator connected with said current producing means, a dust receptacle, a connection for the passage of material from the separator to said receptacle, means for introducing material from said receptacle to said sewer connection, a valve located in the connection from said receptacle, a vent pipe 100 connected with the sewer connection, and a connection from said air producing device with said sewer connection.

8. In combination with a connection to a sewer, means for producing a current of air, 110 a separator connected with said current producing means, a dust receptacle, a connection for the passage of material from the separator to said receptacle, means for introducing material to said separator, a connection for the passage of material from said receptacle to said sewer connection, a valve located in the connection from said receptacle, a connection between said current producing means and said sewer connection, and means for supplying water to 120 the outlet from said receptacle.

9. In combination with a sewer connection, an apparatus for producing a current of air, a separator connected with said current producing means, a receptacle for dirt collected by the operation of said apparatus, a connection for the passage of material from said separator to said receptacle, an outlet from said receptacle to the sewer 130.

connection, a valve in said outlet, a valve to close the inlet to said receptacle, and a connection between said current producing means and sewer connection.

5 10. In combination with a sewer connection, a dust separator, a dust receptacle, a passage for the delivery of material from the separator to said receptacle, a passage between said receptacle and said sewer connection, a valve in said passage to the sewer connection, an apparatus for producing a current of air in said separator, a connection between said apparatus and the sewer connection, and a spraying apparatus located 15 within the discharge from said current producing apparatus.

11. In combination with a sewer connection, a dust separator including a dust receptacle connected with said sewer connection, means connected with said receptacle for producing a current of air, a valve to close the passage from said receptacle to the current producing means, said valve being arranged to close by pressure inside of the receptacle, a valve to close the outlet from said receptacle, and a connection between the exhaust of said current producing means and said sewer connection.

12. In combination with a connection to a sewer, means for producing a current of air, a separator connected with said current producing means, means for introducing material to the separator, a dust receptacle, a connection for the passage of material from the separator to said receptacle, a valve to close the passage between the separator and receptacle, a connection for the passage of material from said receptacle to said sewer connection, and a connection between 40 said current producing means and sewer connection.

13. In combination with a sewer connection, a dust separator including a dust receptacle connected with the sewer, means connected with said receptacle for producing a current of air, a valve to close the passage from said receptacle to the current producing means, said valve being arranged to close by pressure influenced by said current producing means, and a connection between the exhaust of said current producing means and said sewer connection.

14. In combination with a sewer connection, a dust separator including a dust receptacle communicating with said sewer connection, means connected with said receptacle for producing a current of air, a valve to close the passage from said receptacle to

the current producing means, said valve being arranged to close by pressure influenced 60 by said current producing means, and a connection between the exhaust of said current producing means and said sewer connection.

15. In combination with a sewer connection, a dust separator including a dust receptacle communicating with said sewer connection, means connected with said receptacle for producing a current of air, a valve to close the passage from said receptacle to the current producing means, said valve being arranged to close by pressure inside of the receptacle, a valve to close the outlet from said receptacle, and a connection between the exhaust of said current producing means and said sewer connection. 75

16. In combination with a sewer connection, a dust separator including a dust receptacle communicating with said sewer connection, means connected with said receptacle for producing a current of air, a valve 80 to close the passage from said receptacle to the current producing means, said valve being arranged to close by pressure influenced by said current producing means, a connection between the exhaust of said current producing means and said sewer connection, 85 and means for introducing fluid to said receptacle.

17. In combination with a sewer connection, a dust separator including a dust receptacle communicating with said sewer connection, means connected with said receptacle for producing a current of air, a valve to close the passage from said receptacle to the current producing means, said valve being arranged to close by pressure inside of the receptacle, a valve to close the outlet from said receptacle, a connection between the exhaust of said current producing means and said sewer connection, and means for 100 introducing fluid to said receptacle. 90

18. In combination with a sewer connection, a dust separator including a dust receptacle communicating with said sewer connection, means connected with said receptacle for producing a current of air, a valve to close the passage from said receptacle to the current producing means, a valve to close 105 the outlet from said receptacle, and a connection between the exhaust of said current producing means and said sewer connection. 110

IRAH SPENCER.
